DOBBY FINGER FOR LOOMS

Application filed April 23, 1930. Serial No. 446,700.

This invention relates to improvements in dobbies for looms and it is the general object of the invention to provide an improved finger usable on multiple weave 5 dobbies.

In the weaving of towels and handkerchiefs it is customary to employ a multiple weave dobbie having two independent sets of dobbies which cooperate with two 10 different pattern surfaces. A flexible connection is ordinarily introduced between the fingers of the upper auxiliary set and those of the lower primary group which directly 15 control the harness lever hooks. As heretofore employed the cords have been broken or cut by sharp edges on the fingers and it is an important object of my present invention to provide a simple attachment for the 20 finger having a smooth well rounded surface which will not fray or abrade the cord connections.

It is a more specific object of my present 25 invention to provide a metallic ring which is held to a dobbie finger, the wire of which the ring is made being of a diameter less than the thickness of the dobbie finger so that said rings will be spaced from each 30 other sufficiently to permit knots in the cord to pass each other without objectionable contact.

With these and other objects in view which 35 will appear as the description proceeds my invention resides in the combination and arrangement of parts hereinafter described and set forth in the claims.

In the accompanying drawing, wherein a 40 convenient embodiment of my invention is set forth,

Fig. 1 is a vertical section through a dobbie 45 having my invention applied thereto,

Fig. 2 is a detailed horizontal section taken on line 2-2 of Fig. 1,

Figs. 3, 4 and 5 are diagrammatic views 50 showing the manner of forming my improved finger, and

Fig. 6 is an enlarged section on line 6-6 of Fig. 1 showing the relation between the ring and the finger.

Referring to Fig. 1, I have shown a dobbie 55 frame 10 having a cross rod 11 on which

is mounted a plurality of primary lower dobbies 12. The latter are prevented from undue upward movement by a wire 13 and there is provided a primary pattern surface 14 to co-act with the fingers and 55 raise or lower them according to the weave of the pattern. The fingers are made of relatively thick central portions 15 and have reduced guiding wings 16 which project between the dents 17 of a fixed comb having 60 a finger supporting cross bar 18.

A shaft 19 secured in the upper part of the frame has pivoted thereon a plurality of auxiliary fingers 20 which co-act with a second or auxiliary pattern surface 21. 65 There may be one auxiliary finger 20 for each primary finger 12, and each of the upper fingers 20 will be connected to a flexible cord 22 which may preferably be braided and treated to prevent elongation under varying 70 atmospheric conditions.

The pattern surfaces 14 and 21 will be in action alternately, one coming to rest as the other becomes active and the lower fingers will control dobbie hooks which determine the 75 order in which the harness frames not shown will be raised. The auxiliary fingers are not connected directly to the hooks but exert their control through the lower fingers. The matter thus far described is old in the art as 80 shown in patent to Selley No. 955,559.

In carrying my present invention into effect I provide improved means for attaching the lower ends of the cords 22 to the primary fingers 12. Each of the latter may have a 85 shoulder 30 which is slotted as at 31, Fig. 4 to define a pair of compressible lips 32 and 33, respectively. The slot may be of a depth indicated by the dotted line 34 in Fig. 1 and of a sufficient width to receive a wire ring 35. 90 The latter may be endless or a straight wire bent to circular form. In either instance the plane of the ring will be substantially parallel to the vertical sides of the corresponding finger 12. After the ring is inserted in 95 the position shown in Fig. 1 the lips 32 and 33 will be pressed together as indicated in Fig. 5, thereby clinching the ring in place.

It is a desirable feature of my invention to form the ring of wire substantially less in 100

diameter than the thickness of the body 15 of the main finger so that the knots at the lower ends of the cords 22 may pass each other without interference. While I have shown a dobby finger as formed of a solid piece of metal yet there have been proposed and used dobby fingers so constructed that the lips 32 and 33 can be formed of sheet metal.

- 16 1c From the foregoing it will be seen that I have provided a simple form of dobby finger wherein a ring or similar contrivance is clamped or otherwise secured to the finger to receive the lower end of a flexible cord. It 15 will further be seen that the rings are so formed that when several fingers are assembled side by side there will be sufficient space between the rings for the knots in the cords. Furthermore, in forming the rings of wire 20 smooth rounded surfaces are easily provided to prevent wearing of the cords.

Having thus described my invention it will be seen that changes and modifications may be made therein by those skilled in the art 25 without departing from the spirit and scope of the invention and I do not wish to be limited to the details herein disclosed, but what I claim is:

1. In a dobby finger to cooperate with a 20 cord, a pair of normally spaced lips secured to the finger, and a ring located between and held in a substantially fixed relation with respect to the finger by said lips and presenting a surface to cooperate with the cord.
2. In a dobby finger to cooperate with a 25 cord, two lips which are pressed toward each other, and a ring held between and in fixed relation with respect to the finger by said lips and presenting a smooth attaching surface for the cord.
3. A dobby finger to cooperate with a cord, 30 said finger having two parts thereof which are bent toward each other, and a cord holder caught between said parts and held rigid with respect to the finger and presenting a smooth attaching surface for said cord.
4. A dobby finger to cooperate with a cord, 35 said finger formed of material capable of being bent and having two parts bent toward each other, and a cord retainer held between said parts and presenting a smooth attaching surface for the cord.

In testimony whereof I have hereunto affixed my signature.

ELBRIDGE R. HOLMES.
